US00D910944S

(12) **United States Design Patent** (10) **Patent No.:** **US D910,944 S**
Uim et al. (45) **Date of Patent:** **** Feb. 16, 2021**

(54) **CLEANER**

- (71) Applicant: **Samsung Electronics Co., Ltd.**, Suwon-si (KR)
- (72) Inventors: **Donghyuk Uim**, Seoul (KR); **Yeonyoung Nam**, Goyang-si (KR); **Hyoungsub Choi**, Goyang-si (KR)
- (73) Assignee: **SAMSUNG ELECTRONICS CO., LTD.**, Gyeonggi-Do (KR)
- (**) Term: **15 Years**

(21) Appl. No.: **29/681,735**

(22) Filed: **Feb. 27, 2019**

(30) **Foreign Application Priority Data**

- Aug. 29, 2018 (KR) 30-2018-0040337

(57) **CLAIM**

The ornamental design for a cleaner, as shown and described.

DESCRIPTION

FIG. 1 is a front perspective view of a cleaner, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a side perspective view thereof;

FIG. 9 is an enlarged view of the encircled portion 9 in FIG. 1; and,

FIG. 10 is an enlarged view of the encircled portion 10 in FIG. 3.

The broken lines illustrating portions of the cleaner form no part of the claimed design. The dot-dash broken lines encircling enlargement portions of the cleaner form no part of the claimed design.

1 Claim, 7 Drawing Sheets
